UNITED STATES PATENT OFFICE.

ANNA HAGELMAN, OF HOUSTON, TEXAS

VIRGIN-BUST FORMER AND SUPPORTER.

Application filed November 20, 1925. Serial No. 70,249.

This invention relates to improvements in bust formers and the object of the invention is to provide a virgin bust former to retain the bust in true virgin form or to 5 place and build up the bust.

Another object of the invention is to provide an undergarment of this nature in which the cutting, fitting and binding is on a bias of the cloth, particularly the body of the 10 garment, thus ensuring sufficient elasticity for comfort and perfect fitting.

The invention further provides an undergarment of this description which may be worn with bathing suits and décolletté 15 gowns, without being visible.

With the above and other objects in view the invention will be better understood from a perusal of the following description in connection with the accompanying drawing 20 forming part hereof and in which—

Figure 1 is a view of the virgin bust former in position on the wearer.

Figure 2 is a view similar to Figure 1, illustrating a back view.

Figure 3 is a top or plan view of a piece 25 of material folded diagonally upon itself, the outside dotted lines indicating the appearance before folding and the interior lines indicating the cutting lines.

Figure 4 is a front elevational view of the completed bust former fully extended.

Figure 5 is an enlarged detail sectional view of one of the ends of the bust former, the view taken from the inside thereof.

Figures 6 and 7 are cross-sectional views 30 along lines 6—6 and 7—7 of Figure 4, illustrating the binding arrangement.

Figure 8 is an enlarged, detail, fragmentary sectional view showing the manner of 35 forming the central bust seams.

In carrying out the invention, a piece of cloth of closely woven texture is selected, domestic if the garment is to be made of cotton, or satin if a silk garment is desired.

40 However, any closely woven material can be utilized. The bust former is cut from a square of cloth 1, the cloth being first folded diagonally upon itself, as shown in Figure 3, and cut along the dotted lines 2 and the full line 3, the latter line providing, as will be apparent, a true bias cut.

The material of the garment is cut transversely of its length at spaced points to 45 form middle and end portions having edges 4, which are sewn together to form bust recesses or pockets 5, providing central seams

6. This middle portion is a single piece of material and each of the end portions is likewise a single piece of material extending continuously from the middle portion to the end 60 of the former. The extreme edges of the joined portions are then folded backward and are hemmed as at 7 to reinforce the seams and material adjacent thereto. The lower parts of the adjacent edges 4 extend at 65 substantially right angles to the lower edge 3, and the remainders of the adjacent edges 4 are oppositely and substantially equally convexly curved to form the recesses 5, which are symmetrical with respect to the middle 70 and end portions of the former.

To strengthen the ends of the former, an extra thickness of material is stitched to and entirely covered by one face of the material of the former, thus forming the double 75 panel 8 as in Figs. 5 and 6. A double seam, indicated at 9, Fig. 5, unites the two thicknesses, and the second or reinforcing thickness is cut on the "straight" and so positioned that its threads run at an angle to the threads 80 of the material cut on the "bias" to thereby reinforce the same.

The bust former is well bound by cutting bias strips of the same material as the former about one inch in width and turning 85 the edges to provide a binding about one-half inch wide and stitching the binding 10 in place as shown in detail in Figure 7.

For suspending the garment there are employed non-slip or non-drop straps 11, preferably of double-faced satin ribbon, attached 90 perfectly straight to the top of the bust former front seam and attached diagonally at the back but with straight edge, at back at double seam 9.

95 From the foregoing, it will be apparent that the garment provides a bust former and support which will lift, mold and sustain the true bust form, with the advantages of great comfort, being double at the ends and having an even tension at the point of fastening. The non-drop or non-slip straps are also very advantageous and the garment may be worn with bathing suits, décolletté gowns, etc.

100 Particular attention is also again directed to the manner of cutting and constructing the garment on a true bias which is a primary object of the invention.

105 What is claimed is:

110 A bust former comprising a flat strip of material having its lower edge straight from

end to end and cut on the bias, said strip having middle and end portions having their adjacent edges joined together by a plurality of spaced stitched seams, each of said end portions extending continuously from said middle portion to the end of said former, the lower parts of the adjacent edges of said portions extending at right angles to said straight lower edge and the remainders of 10 said adjacent edges oppositely and substan-

tially equally convexly curved to form recesses, the edges of the completed garment having bias bindings, to provide a comfortable, snugly fitting bust former possessing elasticity to permit freedom and comfort in movement, and shoulder straps attached to the upper ends of said seams and to said end portions. ¹⁵

In testimony whereof I affix my signature,
ANNA HAGELMAN.
